UNITED STATES PATENT OFFICE.

HUGO A. FUNK, OF CHICAGO, ILLINOIS, ASSIGNOR OF FORTY-NINE PER CENT TO
ROLLIN C. CONEY, OF CHICAGO, ILLINOIS.

FOUNTAIN PEN.

Application filed November 12, 1921. Serial No. 514,890.

To all whom it may concern:

Be it known that I, HUGO A. FUNK, a citizen of the United States, and a resident of the city of Chicago, county of Cook, and 5 State of Illinois, have invented certain new and useful Improvements in Fountain Pens, of which the following is a specification.

My invention relates to new and useful improvements in fountain pens, and more 10 particularly to self-filling fountain pens. The object of the invention is to provide means for completely depressing the ink sack and for positively expanding or returning said sack to its normal position.

15 A further object is to provide a hinged connection between the lever and the ink sack.

Other objects will appear hereinafter.

The invention consists in the combinations 20 and arrangements of parts hereinafter described and claimed.

The invention will be best understood by reference to the accompanying drawing forming a part of this specification, and in 25 which,

Fig. 1 is a plan view of the pen,

Fig. 2 is a vertical sectional view, taken on line 2—2 Fig. 1,

Fig. 3 is a sectional view similar to Fig. 2, 30 but showing the ink sack depressed,

Fig. 4 is a plan view of the ink sack and parts, without the pen barrel, and

Fig. 5 is an enlarged perspective view 35 of the operating lever and its hinge connection with the pressure plate and ink sack, showing said sack and plate in part.

In the form of my invention illustrated in the drawing I have shown a fountain pen 10 comprising a barrel 11 and an ink 40 sack 12 fastened upon the inner neck 13 of the pen in the usual way. A pressure plate 14 of metal or some suitable material is glued or otherwise firmly fastened or fixed upon the ink sack 12. A tongue 15 is provided on the middle of the plate and may be punched and bent upwards from the material of the plate itself, as shown in the drawings, or may be provided in any suitable form of any suitable material, and soldered or otherwise firmly fastened on said plate. An operating lever 16 of metal of some suitable material, is constructed with a lateral arm 17 for engagement by a fin-

ger, and with a lateral arm 18 having a slot 19 provided therein, said slot extending into 55 the body of the lever 16. The tongue 15 is adapted to operate in said slot, and since it extends farther than the slot 19, it forms a hinge connection between the lever and the pressure bar for positively returning 60 the ink sack to its expanded position. The barrel 11 is provided with a slot 21 to receive the arm 17 of the lever and with a slot 22 to receive the arm 18 and to permit the body of the lever to slide therethrough. 65

In assembling the parts the lever is placed in the pen barrel in its position of rest, as shown in Fig. 2 of the drawing, and the ink sack is introduced into the barrel, the tongue 15 on the ink sack thereby engaging in the slot 19 in the lever.

To refill my improved pen, the lever is first swung laterally at right angles to the pen barrel, as shown in dotted lines in Fig. 2, the ink sack not being actuated by this 75 motion. The lever is then depressed and slid through the opening 22 laterally into the pen barrel, thereby compressing the ink sack, as shown in Fig. 3 of the drawing. The sack may thus be entirely depressed 80 instead of only to the extent of the length of the depressing arm on the operating lever, as in the usual construction on the market. The lever is now drawn outward, and since the tongue 15 extends over the 85 arm 18 of the lever, beyond the end of the slot 19, the sack is positively drawn back into its expanded position. And by thus providing a hinge connection between the operating lever and the ink sack, and a 90

slidable connection between the lever and the barrel, the ink sack is forcefully and 95 positively expanded and filled without depending upon the resilient qualities of the rubber sack as is the case in the constructions now on the market, thus also lengthening the life of the rubber ink sack. By this construction only two narrow slots are required in the pen barrel for the reception of the two arms in the operating lever, instead of 100 a large slot enabling the lever to operate therein, and additional holes for the hinge pins of the lever as in the usual construction, my construction therefore producing a stronger pen barrel.

105 While I have illustrated and described

the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

10 Having described my invention what I claim as new and desire to secure by Letters Patent is:—

15 1. A fountain pen comprising in combination, an ink sack; and an operating member having hinge connection with said sack and being slidably movable in the pen barrel for filling said sack.

20 2. A fountain pen comprising in combination, a flexible ink sack; a rigid member fixedly mounted on said sack; a tongue on said rigid member and an operating member hinged on the tongue on said rigid member, and adapted to fill the ink sack by a movement laterally of the pen barrel.

25 3. A fountain pen comprising in combination, an ink sack having a pressure plate rigidly attached thereto; and a lever hingedly connected with said plate for depressing said ink sack.

30 4. A fountain pen comprising in combination, an ink sack; and an operating member connected to said sack for positively expanding said sack upon the return movement of said operating member.

35 5. A fountain pen comprising in combina-

tion, a flexible ink sack; a pressure plate glued on to said sack; an operating lever slidably extending through a slot in the pen barrel; and connecting means between said plate and lever, enabling said lever to positively compress and expand said sack by said lever moving at right angles to said pen barrel.

6. A fountain pen comprising in combination, a pen barrel provided with slots; an ink sack carrying and having attached thereto a pressure plate; a lever provided with arms normally engaging in said slots; and a tongue on said plate engaging in a slot in said lever, whereby said lever is swingable laterally from the pen barrel without depressing the ink sack, but is movable laterally outward to expand said ink sack.

7. A fountain pen comprising in combination, a pen barrel provided with slots; an ink sack provided with a pressure plate fastened thereon; a lever provided with arms normally engaging in said slots; and connecting means between the lever and plate, whereby said lever is swingable at right angles to the barrel without actuating said sack, and is slidable through one of said slots to positively actuate said ink sack.

In testimony whereof I have signed my name to this specification in the presence of two subscribing witnesses.

HUGO A. FUNK.
